UNITED STATES PATENT OFFICE.

ANDREW C. DAM AND CHARLES H. KIRBY, OF NEW YORK, N. Y.; SAID KIRBY ASSIGNOR
TO SAID DAM.

ELECTRIC HEATER FOR CARBURETERS.

1,115,512.

Specification of Letters Patent.

Patented Nov. 3, 1914.

Application filed April 21, 1911, Serial No. 622,520. Renewed March 7, 1914. Serial No. 823,243.

To all whom it may concern:

Be it known that we, ANDREW C. DAM and CHARLES H. KIRBY, citizens of the United States, residing at New York, in the county of New York, State of New York, have invented a new and useful Electrical Heater for Carbureters, of which the following is a specification.

This invention relates to carbureters and more particularly to means whereby the explosive mixture can be properly heated, the object of the invention being to provide means for heating by electricity, either or both the air and hydro-carbon prior to the admission thereof to the carburetor or any hydro-carbon mixing device or while within and subsequent to leaving said carburetor or any hydro-carbon mixing device.

Another object is to provide an electrical heater which is simple in construction and compact.

With the foregoing and other objects in view which will appear as the description proceeds the invention resides in the combination and arrangement of parts and in the details of construction hereinafter described and claimed it being understood that changes in the precise embodiment of the invention herein disclosed can be made within the scope of what is claimed without departing from the spirit of the invention.

In the accompanying drawings, the preferred form of the invention has been shown.

In said drawings:—Figure 1 is an elevation of a carburetor and its feed mechanism and connections with the present improvements applied thereto and shown with parts broken away. Fig. 2 is a section through a carburetor having the present improvements arranged therein. Fig. 3 is an enlarged section through a portion of the heater. Fig. 4 is a view partly in section and partly in elevation of the fuel intake pipe and showing the heater located therein.

Referring to the figures by characters of reference 1 designates a carburetor having a fuel intake pipe 2 extending therefrom to the engine, not shown, and provided in addition, with an air intake pipe 3. The casing of the float feed has been indicated at 4 and has a liquid fuel pipe 5 extending therefrom and terminating in a nozzle 6 for directing hydro-carbon into the carbureting chamber. A feed pipe 7 opens into the cas-

ing 4 and serves to direct hydro-carbon to the casing from a suitable tank, not shown.

The parts hereinbefore described are all of a well known type.

The fuel intake pipe 2 may be surrounded by a heating coil 8, said coil being housed within a jacket 9 on which the binding posts 10 are secured. The casing of the carbureting chamber may also be surrounded by a heating coil 11 housed within a jacket 12. The casing 4 of the float chamber is shown surrounded by a heating coil 13 and additional coils have been shown upon the pipe 7, the pipe 5 and the air intake pipe 3, these coils being indicated at 14, 15 and 16 respectively. Jackets 17, 18 and 19 are employed for housing said coils and protecting them from injury and preventing objects from coming into contact therewith. An air heating coil 20 may be supported across the inlet end of the pipe 3, this coil being spaced from the pipe so as to permit air to freely enter the same.

It is to be understood that the terminals of the various coils may be placed in circuit with a suitable source of electricity and should all of the heating coils be employed, the hydro-carbon will be initially heated within pipe 7 before entering the float chamber casing 4 and it will again be heated within this casing and within the pipe 5 prior to being discharged from nozzle 6. Air admitted to the carbureting chamber will be heated by the coil 20 and by the heated pipe 3. The hot air and hydro-carbon will be thoroughly mixed in the usual manner within the chamber 1 and will be subsequently heated by the coil 8 on the fuel intake pipe 2. It will be obvious, of course, that, if desired, any one of these heating coils may be dispensed with and the hydro-carbon or the air can be heated at any one of the points mentioned.

By the term carburetor as used it is intended to include not only the carbureting chamber, but also the float chamber and the various pipe connections disclosed in Fig. 1.

In Fig. 2 a carburetor of the "Stewart" type has been shown, the same being provided with a heater arranged therein. This carburetor has an air valve, such as indicated at 21 and which surrounds an aspirating tube 22 extending upwardly from a well 23 in the lower or stem portion of the valve 21. The float in float chamber 24, has been

indicated at 25 and the air intake has been shown at 26, this intake communicating with the compartment 27 surrounding the upper portion of the valve.

5 The heater constituting the present improvements is in the form of two concentric circular bands 28 of insulating material and interposed between these bands are concentric coils of conducting material, such as 10 indicated at 29, said coils being spaced by a circular partition plate 30. Supporting rings 31 or the like may engage the upper edge portions of the parts 28 and 30 and are suspended from eyes 32 or the like projecting 15 from the upper portion of the wall of compartment 27. The conductors 29 are extended to plugs 33 mounted within but insulated from the body of the carbureter and these plugs 33 are electrically connected to a 20 suitable source of electrical energy.

From the foregoing it will be seen that the fluid contents of the carbureter, before leaving the same through the outlet 34, will be thoroughly heated by the heater suspended 25 within the compartment 27, the air being brought into intimate relation with this heater during its circulation through the carbureter.

If preferred, a heater, such as has been

30 illustrated in Figs. 2 and 3, may be placed within the fuel intake pipe 35 connecting the carbureter with the engine, this arrangement being illustrated in Fig. 4 wherein the heater is shown at 36, the same being supported within the pipe 35 by suitable brackets 37. A nozzle 38 for directing fuel into the pipe 35 is preferably extended into the heater so that, as the fuel is discharged from the nozzle it will be promptly heated.

35 40 What is claimed is:—

The combination with a carbureter having an aspirating tube and an air valve surrounding the tube, of a ring-like electric heater suspended within the mixing chamber and extending around the valve and aspirating tube and spaced therefrom and from the wall of the chamber, the gases in the chamber being free to circulate through and around the heater.

45 50 In testimony that we claim the foregoing as our own, we have hereto affixed our signatures in the presence of two witnesses.

ANDREW C. DAM.
CHAS. H. KIRBY.
